UNITED STATES PATENT OFFICE.

SIMON W. WARDWELL, JR., OF WOONSOCKET, RHODE ISLAND, ASSIGNOR
TO WILLIAM P. EARLE, TRUSTEE, OF BROOKLYN, NEW YORK.

THREAD-GRIPPING DEVICE.

SPECIFICATION forming part of Letters Patent No. 396,183, dated January 15, 1889.

Application filed August 26, 1886. Serial No. 211,944. (No model.)

To all whom it may concern:

Be it known that I, SIMON W. WARDWELL, Jr., of Woonsocket, Providence county, Rhode Island, have invented an Improved Thread-Gripping Device, of which the following is a specification.

My invention has for its object to grip a traveling thread or cord absolutely at intervals without the use of the usual movable gripping devices, and this object I effect by forming a V-shaped grip-slot in some part of the machine and by deflecting the thread out of its normal path into said slot whenever it is to be gripped, as fully set forth hereinafter, and as illustrated in the accompanying drawings, in which—

Figure 1 is an end view showing part of the revolving take-up of a sewing-machine and illustrating my improvement. Fig. 2 is a plan of the parts shown in Fig. 1. Fig. 3 is an enlarged section on the line 1 2, Fig. 2. Fig. 4 is a section on the line 3 4, Fig. 2.

For the purpose of illustrating my invention I have shown it in connection with the take-up contrivance constituting the subject of an application for Letters Patent filed by me on the 7th day of January, 1886, Serial No. 187,907. It will be understood, however, that the invention is applicable to other contrivances where it is required to temporarily bind and release a moving thread or cord.

The parts designated by letter represent parts of the said take-up contrivance, A being a revolving wheel provided with peripheral ribs *b b*, notched to form shoulders *x x* to catch the thread as the wheel revolves in the direction of its arrow.

C is the spool, mounted on a fixed spindle, *d*.

E is a bracket supporting or constituting the tension-head F. The tension-head is a terminal widened portion of the bracket, the ends forming ears *e e'*, the former being cut away to receive a grip-block, 7, which is bolted to the ear by a screw-pin, 9, at the outer end, the inner face, 4, of the block and corresponding face, 3, of the head being at right angles to the direction of the ribs *b b*.

In the ear *e'* is a slot, *y*, through which the thread *z* is conducted from the spool C, and

thence passes across the end of the head F to and between the faces 3 4 of the grip-block and head and past a guide-pin, 12, and through suitable guides to the needle.

The bracket E supports a retaining-bar, D, 55 having a terminal hook, *f*, with an inclined edge, *v*, below a shoulder, *u*, and the shoulders *xx* of the ribs *b b* catch upon the transverse portion of the thread and carry it onward until it is brought over and rides up the inclined edge *v*, and is thereby released from the shoulders *x*, but catches upon the shoulder *u*, and is there for a moment retained until the projecting parts of the ribs pass from opposite the retaining-bar, when the thread will slip 60 from the shoulder *u* and again take a straight course, as shown in dotted lines, Fig. 2, and as fully set forth in the specification of my other application before referred to.

It is desired to grip the thread absolutely 70 at the point where it is in contact with the head F before crossing the ribs *b b*, and this grip is effected with certainty and automatically by the grip-block 7. The lower face of the grip-block is inclined upward at the inner corner, as shown in Fig. 3, this inclined face 8 forming, with the upper face, 2, of the ear *e*, a narrowing slot, 5.

As long as the thread is in the position shown in dotted lines, Fig. 2, it can pass freely between the faces 3 4, sliding over the face 3; but the instant the shoulders *x x* move the thread out of the line of the face 3 it is carried into the slot 5, and is wedged therein so firmly that it cannot be drawn longitudinally, 85 as before, and the loop or bend formed by the moving shoulders *x x* must be made wholly from thread drawn from the forward end of the machine. The thread is thus absolutely gripped until it is released from the shoulder 90 *u*, when it resumes the direction shown in dotted lines, Fig. 2, passing easily without friction or resistance from the notch 5, into which it is again carried and wedged when next deflected from its straight course.

To keep the thread taut, a slight resistance is applied thereto at some point between the grip-slot and the spool. Different devices, which I term "tension" devices, may be employed for this purpose. Thus a thin spring- 95 100

plate, I, is pressed against the end of the head F by a spring, J, coiled round a screw-bolt, G, which passes through a hole in the plate and serves as a means of regulating the spring-pressure. The thread is conducted between this plate and the face of the head F, and is thus maintained taut, so that the hook in making the loop will not draw down too much thread—that is, will not draw from the spool more thread than was taken up by the previous stitch.

In the above-described device the principle which governs ordinary gripping devices is reversed. In such ordinary devices the gripping is effected by bringing together movable parts, either to pinch the thread directly or to apply friction to some part (as a grooved disk) carrying the thread.

In the above-described device there are no movable clamping-faces, and the action results automatically from the thread being deflected from the line of its normal path to the needle, and the thread is wedged in the notch while the take-up draws up and tightens the stitch, and is released simply as the result of resuming its normal position. Thus by the action of the grip (which prevents the possibility of any slipping of the thread) I insure the drawing both up and down of a constant quantity of thread and the placing of the lock at a given point with reference to the top of the needle-plate without regard to the thickness of material being sewed.

As the grip only acts while the thread is being drawn up, it may not be clear at first how it insures the drawing down by the hook of a constant quantity of thread. This will be evident, however, by supposing that in place of this device there is a tension device through which it is possible for the thread to slip, and that the hook has drawn sufficient thread from the spool to form a new stitch and has completed its loop. For some reason (as a hard spot in the material, pinching by the presser-foot, &c.) this loop may offer more resistance to the action of the take-up than the one before it, the increased resistance being sufficient to cause the thread to slip through the tension and a small quantity to be drawn from the spool by the take-up.

When the take-up reaches the extreme limit of its draft, it will fail to tighten the stitch by just the amount of thread which it drew from the spool, and which will appear on the bottom of the material in the form of a loop. When the hook takes its next loop, it will draw up a portion (possibly the whole) of the loop left by the take-up, and will only draw from the spool what thread it needs in addition to the amount drawn up to form the next stitch. The above-described grip by absolutely preventing any such draft from the spool by the take-up and insuring the regular drawing up of a constant quantity of thread leaves the same quantity to be drawn down by the hook minus the amount required for the next stitch, the only responsibility of the hook being to

draw the deficiency from the spool. The tightness with which the thread is wedged in the grip-slot is in proportion to the strain it bears while being drawn up by the take-up. Thus, when sewing thick material with a large thread, the drawing strain will be heavy and the thread will be very tightly wedged in the slot, while with thin material and small thread the drawing strain will be proportionately less and the thread will be less tightly wedged. In either case it will be sufficient to hold the thread absolutely. By making the amount of strain on the thread in drawing up and tightening the switch the measure of the resistance in the grip-slot to the action of such strain I infallibly secure the automatic regulation of the grip and its adaptation to the character of the thread. This automatic adaptability is very important. Theoretically, any pinching or flattening of the thread is an injury. Practically, it is impossible to avoid some pinching of the thread; but it is possible to avoid pinching it unnecessarily.

In those gripping devices which act by motion against the thread the grip must be strong enough to hold the largest thread, and in using small thread with such a grip it is liable to be pinched off or injured so that it will easily break. The great superiority in this respect of the above-described device, where the thread automatically regulates its own grip, will be apparent.

This device takes the place of all tension devices for resisting the action of the take-up, doing away with tension, as illustrated by those devices, and substituting a rigid point of anchorage for the thread, placed in such relation to the take-up that, invariably, when the latter has reached the extreme point of its throw—or the extreme limit of its draft—the stitch will be properly tightened without regard to the thickness of material being sewed. Thus the operator is entirely relieved from any consideration of the question of tension.

I have shown the device as formed by a notched head and detachable block, as this permits the ready construction; but it will be evident that a V-shaped notch may be cut in the head or any other part of the machine. Although I have illustrated my improved gripping device in connection with a revolving take-up of a peculiar construction, it will be evident that it may be used with take-up devices of other forms and with other appliances for deflecting the thread from its normal path into the grip-slot at such times as it must be gripped.

It will be evident that the grip-slot may be formed in different parts of the machine.

Without limiting myself to the precise construction and arrangement of parts shown, I claim—

1. The combination, in the take-up of a sewing-machine, of a part of the machine having a V-shaped notch adjacent to the normal path of the thread, a deflector whereby said thread

- is carried into said notch and there gripped as the thread is taken up, and a thread-releaser arranged to disconnect the thread from the deflector, substantially as described.
- 5 2. The combination of the stationary head F, a revolving shouldered thread-deflecting disk arranged adjacent thereto, a thread-gripping notch in said head at right angles to the disk, and a thread-releasing device, as 10 D, substantially as described.
3. The combination of the thread-guides, the stationary V-shaped thread-grip adjacent to the normal path of the thread, a revolving take-up which deflects the thread into the 15 thread-grip during its operation, and a releasing device which disengages said thread from the revolving take-up, substantially as set forth.
4. The combination, with the thread-guides, 20 a stationary thread-receiving notch, and a revolving deflector which deflects the thread from its normal path into said notch, where it is positively held, of a cast-off or releasing device for disengaging the thread from the deflector and notch and a pressure device arranged to apply tension to the thread between the spool and notch, substantially as 25 set forth.
5. The combination, with the take-up of a 30 sewing-machine, of a head, F, arranged between the spool and take-up, having the ears e e', one of said ears having formed in it a thread-guide slot and the other being provided with a detachable grip-block, 7, arranged to form a second guide-slot and bevelled at the lower face to form a grip-notch, substantially as described.
6. The combination of the head provided with a thread-grip notch, a revolving take-up provided with a rib, a thread-releasing device, and a retaining-bar having a shoulder against which the thread is held until the rib has passed the shoulder, substantially as described. 40
7. The combination of the take-up, consisting of the revolving ribbed and shouldered disk and retaining-bar having an inclined edge and shoulder, and a bracket or head having a V-shaped notch arranged to receive the thread when deflected by the take-up, substantially as set forth. 45
8. The combination, with a sewing-machine, of a stationary head, F, provided on one side with a thread-guiding slot and on the other with a thread-gripping notch, a revolving 50 shouldered disk, and a bar, D, supported by said head and having an inclined edge and shoulder, substantially as described.
9. The combination, in a sewing-machine, of a stationary head, F, having a thread-guiding slot and a thread-gripping notch, a tension device intermediate of said slot and notch, a revolving shouldered disk arranged to deflect the thread into said thread-gripping notch, and a device carried by the head for 55 releasing the deflected thread from the shoulders of the disk, substantially as described.

In testimony whereof I have signed my name to this specification in the presence of two subscribing witnesses.
